UNITED STATES PATENT OFFICE.

ALBERT E. STRONG, OF PATERSON, NEW JERSEY.

AUTOMATIC FROGLESS SWITCH.

SPECIFICATION forming part of Letters Patent No. 321,920, dated July 7, 1885.

Application filed August 6, 1884. (No model.)

To all whom it may concern:

Be it known that I, ALBERT E. STRONG, a citizen of the United States, residing at Paterson, in the county of Passaic and State of New Jersey, have invented a new and useful 5 Automatic Frogless Railroad-Switch, of which the following is a specification, reference being had to the accompanying drawings, forming part thereof, in which—

10 Figures 1 and 2 are plan views; Figs. 3 and 4, perspective views of parts in detail; Fig. 5, a cross-section near the center of Fig. 4.

Fig. 1 shows the position of railroad-rails of the main line as originally laid, being clamped 15 together as firmly as is possible in the construction of railroads; and my switch can be placed at any point in the main line that is named without displacing, cutting, or in any way disconnecting the rails of said main line, 20 they being left as originally laid. Fig. 2 shows how this is accomplished—viz., by the three pieces A, B, and C, operated by a series of levers, or a compound leverage consisting of the levers D', D², and E.

25 A represents a heavy cheek-piece placed at the outside of inner rail and overlapping the same.

B is an inclined piece lying on the inside of inner rail, and is secured by a guard-block, 30 L, with a gradual rise sufficient to allow the wheels to pass over the main rail to the cheek-piece A, thence to siding-track K.

C represents a cheek-piece lying inside of outer rail, tapering to a point, in order to allow 35 the wheels to pass from main rail onto said cheek-piece, the flange of wheels passing inside of said cheek-piece, thus throwing the opposite wheels onto inclined piece B and over cheek-piece A, thereby throwing or conducting 40 the train from the main track onto the siding-track K with absolute safety. The inclined piece B swings on a pivot at the journal I, and is so constructed that the wheel-flange enters as a wedge between B and the main rail, forcing 45 it away from the main rail. The wheel-flange acts on the piece B as it does on the pointed piece C. In passing through the switch, the tread of the wheel resting on the main rail or passing along the same in the direction of the arrow, Fig. 2, the outside edge 50 of the tread of wheel helps to displace the cheek-piece A. The pivoted end of the in-

clined piece B is much lower than the flange of wheel, and the movable end is on a level with the main rail and curved sufficiently to 55 allow the flange to act as a wedge between the two. The rod connecting B and lever E contains an expanding spring, H, which readily permits the separation of B from the main rail M by the flange of wheel. The 60 pieces A B C are firmly secured in metal chairs, which form journals, and are marked I I I, and are securely spiked or bolted to the ties or plates for the purpose of safety and strength. All the journals I I I are placed so 65 as not to interfere with wheels on main rail, and so as to permit the pieces to be acted upon by the levers D' D² E. The rod marked S connects the cheek-pieces A and C, and is itself connected with the lever D'. D' is connected with the inclined piece B at point 70 marked X. The levers D' and D² are pivoted to lever E at the points marked T T, by which means levers D' and D² act in opposite directions, thus moving the pieces A and C in one way 75 and piece B in the opposite direction when in operation. The switch must of course remain locked, as ordinary switches are, unless it is desired to use the switch by hand-lever, with which my switch may be provided, as appears 80 by F in the drawings, which shows F² an upright post in center of lever E, around which lever E is fastened. Said upright may display signals, as desired. It is at its lower end embedded in a socket of metal, and at its upper 85 end it is secured as usual, and is only turned when used as hand-lever switch. In levers D' and D² are placed, at point marked H H, springs, which, in combination with the pieces A, B, and C, constitute the automatic portion 90 of my switch.

In Figs. 1 and 4 is seen how I dispense with the use of a frog, which is generally used in all switches. A', Fig. 1, represents an overlapping cheek-piece, similar to A in Fig. 2, 95 and is placed on inner side of inner rail of main track, overlapping the same. B' is an inclined lever outside of the inner rail of the siding-track K. Under said inclined lever are secured inclined metal blocks, on which inclined lever moves, and outside of said inclined lever are metal braces or guides. The lever B' is connected with cheek-piece A' by rod or bar marked C. D D show a series of heavy springs

attached to the outside of lever B, and anchored in socket-plates, which are securely fixed to ties similar to the metal chairs in Fig. 2.

The pieces A in Fig. 2 and A' in Fig. 1 may be made in a solid piece or in two pieces, the overlapping plates being made so as to easily be adjusted and removed in case of wear.

The switch, as shown in Fig. 2, operates as follows: A train passing along main track to the points marked P P, the flange on wheels passing between the outer rail and the cheek-piece C forces the cheek-piece C and the overlapping cheek-piece A and the inclined piece B clear from the main rails, and having passed the points of the switch O O the switch itself is closed automatically by reason of the springs H H in levers D' and D', said springs forcing the overlapping cheek-piece A over the inner rail of main track, and at the same time forcing the pointed cheek-piece C against the inner side of outer rail of main track, securely closing the switch, and thereby forming a solid passage-way from the main track onto the siding-track K. The passage from left to right, Fig. 2, is rendered more easy and safe by the gradual ascent of the inclined piece B, which rises a little above the main rail, thus allowing the wheels to pass onto the overlapping cheek-piece A, which is itself provided with a flange.

The operation of my invention, as shown by Figs. 1 and 4, is as follows, viz: A train passing on siding-track K moves onto the inclined lever B', forcing lever B' down on springs D D'. Lever B' being connected by rod C' to the overlapping cheek-piece A', when the lever B' is forced down on the springs D D', the overlapping piece A' is naturally drawn over the

main rail at point 20, thus forming a solid passage-way over the inner rail of the main track onto the siding-tracks K, leaving the main rails intact. After passage of the train past point 20, the inclined lever B' being relieved of weight of train, it is forced back obliquely by the springs D D to its position overlapping the rail and by the same movement, thereby causing the cheek-piece A' to leave the inner rail of the main track at the point 20, and thus the main line remains free and clear.

A train can pass in either direction from one track to another, as above described, and, as above stated, a switch may be placed at any point without moving a main rail or disconnecting one.

The switch above described may be used as the ordinary hand-lever switch which is employed in railroading, or it may be used automatically, as set forth.

Having described my invention, I desire to secure it by Letters Patent, and claim—

The combination of the unbroken main rail M, siding-rail K, the flanged overlapping cheek-pieces A, and pointed piece C, connected by bridle-rod S, inclined piece B, with flange at loose end, compound lever E, rods D' and D'', springs H, expanding and contracting inclined lever B', provided with springs D, and connected with overlapping piece A' by bridle C', all constructed substantially as shown and described, and for the purpose set forth.

ALBERT E. STRONG.
